UNITED STATES PATENT OFFICE.

IRA D. GEIGER, OF PHILADELPHIA, PENNSYLVANIA.

ROTARY PUMP.

Application filed February 11, 1924. Serial No. 692,146.

To all whom it may concern:

Be it known that I, IRA D. GEIGER, a citizen of the United States, residing at Philadelphia, in the county of Philadelphia and State of Pennsylvania, have invented new and useful Improvements in Rotary Pumps, of which the following is a specification.

This invention relates to rotary pumps, and an object of the invention is to provide 10 a rotary pump which will develop a relatively great amount of out-going force in proportion to the size of the pump and the power employed for operating it.

Another object of this invention is to provide 15 a rotary pump, which is adjustable to permit varying of the capacity of the pump, when desired, permitting the same pump to be utilized with a relatively low capacity for one purpose or change to increase the 20 capacity without materially decreasing the outlet force of the pump.

A still further object of the invention is to provide a rotary pump as specified, which includes a rotor composed of a plurality of 25 discs laterally corrugated at acute angles with respect to the radii of the discs, which discs are disposed in sidewise relation to provide a plurality of circumferentially spaced buckets or pockets which radiating 30 within the stator of the pump create a suction and provides space for receiving the fluid being pumped.

A still further object of this invention is to provide a rotary pump as specified, which 35 may be utilized as a turbine or blower, by reversing the direction of rotation of the rotor.

Other objects of the invention will appear in the following detail description, and in 40 the accompanying drawings wherein:

Figure 1 is a side elevation of the improved pump.

Figure 2 is a longitudinal section through the pump.

Figure 3 is a vertical cross section through the pump taken on the line 3-3 of Figure 1.

Figure 4 is a side elevation of one of the rotor discs or plates.

Figure 5 is an edge elevation of one of the 50 rotor discs or plates.

Figure 6 is a fragmentary view of the shaft of the rotor.

Figure 7 is an inner face view of the stationary stator end.

Figure 8 is a face view of the movable or 55 adjustable stator end.

Referring more particularly to the drawings, the improved rotary pump comprises a stator 1 which includes the substantially tubular or cylindrical body 2, having the 60 end plates 3 and 4 attached thereto in any suitable manner. The body 2 has the inlet 5 and the outlet 6 formed thereon in any suitable manner, so as to permit the flow of fluid through the pump. The end plate or 65 head 3 is recessed in its inner surface to provide the spaces 7 and it has a relatively long bearing 8 formed axially thereon on the outer end of which a suitable stuffing box 9 is mounted. The shaft 10 of the rotor 70 structure 11 is rotatably carried by the bearing 8 and it has a rectangular portion 12, formed thereon at one end of which a collar 13 is mounted, while a reduced threaded portion 14 is provided at the opposite end of 75 rectangular portion. The rotor plates or discs 15 are provided with axial rectangular openings 16 which fit over the rectangular portion 12 and connect the discs to the shaft 10 for rotation therewith. The discs 15 are 80 corrugated or cupped laterally, as clearly shown in Figures 2 and 5 of the drawings, and the corrugations are disposed at acute angles with respect to the radii of the discs to provide sufficient incline to the pockets as 85 indicated at 17 which are formed by the various corrugations to insure the creating of the necessary and proper suction through the pump. The discs are disposed in side- 90 wise relation, one with respect to the other, as clearly shown in Figure 2 of the drawings, thus providing a plurality of circumferentially spaced pockets or buckets, certain of which are substantially circular shaped in 95 cross section, the outer sides of the outer discs are substantially semi-circular in cross section.

In the drawings, four of the discs 15 are shown, but it is to be understood, that any number of the discs may be utilized, without departing from the spirit of this invention and depending upon the capacity of pump desired. To permit variation or adjustment of the capacity of the pump, an 100 adjustable end abutment 20 is positioned 105 within the stator 1 and is carried by a relatively large threaded stem 21 which threads through the end 4 and is adjustable to permit variation of the capacity space between its inner surface, and the inner 110 surface of the head 3, for permitting variation of the number of discs 15 employed to

permit variation of the capacity of the pump. The inner end of the head 3, and the inner surface of the adjustable abutment 20 are provided with beveled cut-out portions 22 which gradually increase in depth from one end to their other ends, as indicated in Figures 7 and 8 of the drawings. These cut-out portions are provided to permit spaces at the ends of the rotor 11, to allow the proper circulation of fluid through the pump.

By particular references to Figures 3 and 4 of the drawings, it will be noted that the corrugations on the discs 15 terminate at their inner ends outwardly of the center 15 of the discs, thereby providing connecting spaces adjacent to the axis of the discs, between the various pockets of the rotor to allow circulation of the fluid therethrough.

A suitable air chamber 23 of any appropriate construction may be carried by the stator 1 and a relief valve 24 is provided to permit the relieving of the interior of the pump of air, when starting it.

It is, of course, to be understood, that the invention may be constructed in various other manners and the parts associated in different relations, and therefore, I do not desire to be limited in any manner except as set forth in the claims hereunto appended.

What I claim is:

1. In a rotary pump, a stator, a rigid abutment at one end of the stator, an adjustable abutment within the stator, a rotor rotatable within the stator between said adjustable and rigid abutments, said abutments provided with arcuate cut-out portions gradually increasing in depth as they curve towards the outlet of the stator.

2. In a rotary pump, a stator, a rotor 40 rotatably mounted therein, and composed of a plurality of transversely corrugated discs disposed in sidewise engagement to provide a plurality of circumferentially spaced pockets, said corrugations terminating at 45 their inner ends outwardly of the axis of the disc to provide communicating spaces between the pockets, a rigid abutment at one end of the stator and adjustable abutment within the stator.

3. In a rotary pump, a stator, a rigid abutment at one end of said stator, an adjustable abutment within the stator, said abutments provided with circuit cut-out portions, gradually increasing in depth as 55 they curve toward the outlet of the stator, a rotor within the stator and composed of a plurality of transversely corrugated discs disposed in sidewise engagement one with the other to provide a plurality of circumferentially spaced pockets.

4. In a rotary pump, a stator, a rigid abutment at one end of said stator, an adjustable abutment within the stator, said abutments provided with circuit cut-out 65 portions gradually increasing in depth as they curve toward the outlet of the stator, a rotor within the stator and composed of a plurality of transversely corrugated discs disposed in sidewise engagement one with the other, to provide a plurality of circumferentially spaced pockets, said corrugations terminating at their inner ends outwardly of the axis of the discs to provide communicating spaces between said pockets.

In testimony whereof I affix my signature.

IRA D. GEIGER.
